PRODUCTION OF SATURATED GASOLINES
WITH INCREASED ANTIKNOCK PROPERTIESRichard M. Deanesly, Hinsdale, Ill., assignor to
Universal Oil Products Company, Chicago, Ill.,
a corporation of Delaware

Application December 26, 1951, Serial No. 263,429

7 Claims. (Cl. 196—49)

1

This invention relates to a combination process designed to convert certain paraffinic gasoline fractions into a fuel more desirable for use in an internal combustion engine. More specifically, the invention concerns a combination of cracking, reforming, and alkylation processes for converting a saturated gasoline to an improved motor fuel product of higher octane number and lower volatility.

It is widely recognized that the motor fuels known as natural and straight-run gasolines, that is, the liquid hydrocarbons recovered from natural gas and distilled from petroleum crudes, respectively do not fully satisfy all of the optimum requirements of a motor fuel for use in internal combustion engines of the spark-firing type, particularly since the increase in compression ratios for internal combustion engines of recent design. This inherent deficiency in the combustion properties of natural and straight-run gasoline is based upon the characteristically low octane number of the liquid straight-chain paraffinic and naphthenic hydrocarbons present in such gasoline fractions. The normally liquid, paraffinic hydrocarbon vapors recovered from natural gases include a relatively large proportion of components boiling below about 200° F. and a considerable proportion of these hydrocarbons (relative to the higher boiling hydrocarbon components) consists of the relatively volatile butanes and pentanes which increase excessively the vapor pressure of gasoline fractions from other sources if blended therewith in too large a proportion. It is therefore evident that to effect an improvement in the volatility characteristics of natural and straight-run gasolines for motor fuel use, at least the light ends of these fractions must be converted into less volatile hydrocarbons generally of greater molecular weight. Furthermore, any improvement in the anti-knock properties of these hydrocarbons must involve a further basic alteration in structure of at least a portion of the hydrocarbon components from essentially straight-chain configuration to a branched-chain or aromatic structure. The present invention provides a process for converting separate portions of a natural and/or straight-run gasoline feed stock whereby the combustion properties of the gasoline are improved for use in an internal combustion engine; the provision of a practical means to effect such conversion is broadly the intended object of this invention.

In one of its embodiments the present invention concerns a process for improving the volatil-

2

ity and anti-knock characteristics of an essentially paraffinic gasoline boiling range fraction for use in an internal combustion engine of the spark-firing type which comprises separating said gasoline into a relatively volatile fraction and a relatively higher boiling fraction, subjecting said volatile fraction to a hydrocarbon cracking reaction, separating a light hydrocarbon fraction from the product of said cracking reaction, subjecting said higher boiling fraction to a reforming reaction, separating an intermediate boiling range fraction from the product of said reforming reaction, subjecting said light hydrocarbon fraction and said intermediate boiling range fraction to a combination polymerization-alkylation reaction, and recovering the remaining normally liquid fractions boiling up to about 400° F. from the products of said cracking, reforming and polymerization-alkylation reactions as an improved gasoline motor fuel.

A more specific embodiment of the invention relates to a process for improving the volatility and anti-knock properties of a gasoline fraction comprising essentially saturated hydrocarbons which comprises separating a fraction having an end boiling point of from about 200° to about 300° F. from said gasoline, subjecting said fraction to thermal cracking, separating a fraction containing C₃ and C₄ olefinic hydrocarbons from a product of said cracking reaction, subjecting the remainder of said gasoline to a catalytic hydrocarbon reforming reaction, separating a fraction boiling from about 160° to about 350° F. from the product of said reforming reaction, subjecting said C₃ and C₄ olefin-containing fraction and said 160° to 350° F. fraction to a catalytic polymerization-alkylation reaction, combining the remaining normally liquid fractions boiling up to about 400° F. from the products of said cracking, reforming and polymerization-alkylation reactions to form an improved gasoline motor fuel.

The present combination process is particularly effective when utilizing a charging stock comprising a natural gasoline product, since a large proportion of the latter feed stocks consists of hydrocarbons having poor detonating properties in internal combustion engines, the hydrocarbons comprising straight-chain paraffinic components of relatively low, and at best, of only mediocre octane number ratings which tend to predetonate and produce a resulting knock when ignited under compression in a spark-fired engine. The process, however, may also be applied with substantially similar advantages to the conversion of straight-run gasoline fractions recovered from

petroleum crudes of any available source containing predominantly naphthenic and paraffinic hydrocarbons, particularly the relatively volatile, initial boiling ends of these fractions. The process may also be applied to the gasoline boiling range fraction of a destructively hydrogenated hydrocarbon mixture in which straight-chain paraffinic hydrocarbons are also present as a result of hydrogenation which accompanies cracking of the higher molecular weight components of the feed stock into hydrocarbons containing fewer carbon atoms per molecule. It is noted that although the process is particularly effective and economically advantageous when applied to predominantly paraffinic feed stocks, the advantages of the present method of conversion are also obtained for feed stocks containing olefinic and/or aromatic hydrocarbons, preferably in minor proportion, which may also be present in admixture with the paraffinic and naphthenic hydrocarbons comprising the feed stock, without departing from the essential operation of the process. In characterizing the present feed stocks as essentially paraffinic gasoline boiling range fractions, it is intended to specify thereby hydrocarbon mixtures comprising aliphatic paraffins as well as cycloparaffinic or naphthenic components, which undergo cracking, isomerization and dehydrogenation to yield the present improved gasoline fuel products.

The invention is further described with respect to various alternative flow arrangements as well as the preferred means for effecting the desired conversion in the accompanying flow diagram and in the description which follows. For the sake of simplicity, the process will be described with reference to a feed stock comprising a natural gasoline containing C₄ and higher paraffinic hydrocarbons predominantly and boiling up to about 400° F.

Referring to the accompanying diagram, a suitable saturated gasoline fraction, such as the present natural gasoline feed stock containing C₄ paraffinic hydrocarbons and boiling up to about 400° F., is fractionated into low boiling and high boiling cuts in a primary fractional distillation column 1 having feed stock charging line 2 through which the natural gasoline is fed into the process flow. The low boiling cut, having an end boiling point generally of from about 200° to about 300° F. and preferably a boiling range from the initial boiling point of the fraction to about 275° F., is separated from the natural gasoline and removed from fractionation unit 1 through line 3. The remaining higher boiling fraction, comprising the remainder of the natural gasoline boiling up to the end boiling point of the feed stock is separated in distillation column 4, removed therefrom through line 4, and treated as hereinafter described.

The process of the present invention is designed to convert the low boiling components of the natural gasoline fraction, consisting largely of volatile, paraffinic hydrocarbons of low or only intermediate octane number into olefins which may be subsequently converted into higher molecular weight alkylate and polymer hydrocarbons of lesser volatility and of higher anti-knock value. The conversion of the low boiling fraction into principally olefinic hydrocarbons is accomplished in the present process by subjecting the fraction to temperatures and pressures sufficient to effect a thermal cracking reaction. Thermal cracking of the low boiling fraction of the feed stock is obtained at pressures of from atmospheric to ap-

proximately 2,000 lbs. per square inch or higher, but preferably at pressures of from about 100 to about 1,000 pounds per square inch at temperatures of from about 700° to about 1200° F., the preferred range being from about 900° to about 1100° F.

The low boiling fraction of the natural gasoline feed stock, such as the C₄-275° F. fraction is charged into cracking reactor 5 at the above hydrocarbon cracking conditions, the cracked products being removed from the reactor through line 6 and charged into a separation unit, such as distillation zone 7, wherein the conversion products of the cracking reaction are separated into various component fractions based upon their boiling points. Separation zone 7 is preferably a series of absorbers, stabilizers and/or distillation columns wherein the light gases such as hydrogen, methane and C₂ components of the product are separated as a gaseous fraction which is removed through line 8 for use in any manner desired, such as fuel for the refinery heaters, etc. A resulting stabilized fraction boiling from about 100° to about 400° F., and preferably from about 200° to about 400° F. removed from zone 7 contains hydrocarbon components particularly desirable for motor fuel use, not only because of the inclusion in this fraction of components which have greater anti-knock properties, but also because of their desirable boiling range for motor fuel use from the standpoint of vapor pressure; this fraction is removed from separation zone 7 through line 9 and is sent to storage or to blending tanks for mixing with the gasoline boiling range products of other units of the present process. A fraction comprising the relatively low molecular weight olefinic hydrocarbons produced in cracking unit 5, such as propylene, n-butylene, isobutylene and the amylenes, boiling up to about 100° F., and preferably up to about 200° F., including hexenes and higher boiling homologs, is removed from zone 7 through line 10 and charged into polymerization-alkylation reactor 11 wherein the latter fraction is reacted with an aromatic-containing fraction derived from the reforming stage of the present process, hereinafter described.

The production of olefins in the present process by splitting the paraffinic components of the natural gasoline feed stock provides a source of hydrocarbon-reactive feed stock which upon polymerization or condensation with aromatic hydrocarbons yields a polymer or alkylate product boiling in the gasoline range having superior anti-knock properties which make it particularly suitable for use as a motor fuel in internal combustion engines. The present process flow provides a unit, that is, alkylation-polymerization zone 11, wherein the olefin-containing fraction (comprising C₃ olefins and higher molecular weight olefinic components boiling up to about 200° F.) is combined with the aromatic hydrocarbon fraction of the present reforming unit, hereinafter described, and reacted in unit 11 in the presence of a particular catalyst which effects substantially simultaneous olefin polymerization and alkylation of the aromatic hydrocarbons charged thereto with said olefinic hydrocarbons. The catalyst and process conditions maintained in reactor 11 are hereinafter described in greater detail.

Referring again to the higher boiling fraction separated from the natural gasoline feed stock in primary fractionating zone 1, having an initial boiling point generally of from about 200° to about

300° F., and preferably a boiling range of from about 275° F. to the end boiling point of the natural gasoline feed stock is removed from zone 1 through line 4 and charged into reforming reactor 12 to convert the relatively low octane number straight-chain paraffinic components of the feed stock into isoparaffinic hydrocarbons of more branched-chain structure, and of higher octane number. In addition to such desirable conversion of the aliphatic components of this fraction, naphthenic hydrocarbons contained in the fraction are converted by means of the dehydrogenation and isomerization reactions occurring during the reforming conversion to aromatic hydrocarbons. The reforming conversion of the present process is effected in the presence of a reforming catalyst selected from certain catalytic composites having such properties for promoting the reforming conversion. The feed stock to the reforming reactor 12 is desirably reacted at the reforming conditions in the presence of an atmosphere of hydrogen which may accompany the hydrocarbon fraction into the reforming reactor 12 or charged separately through line 13, generally in an amount of from about 2 to about 6 molar proportions, based upon the hydrocarbon feed.

The preferred reforming catalyst for effecting the conversion zone 12 comprises a composite of a platinum group metal, such as platinum itself or palladium with alumina and may optionally contain a halogen component in combination therewith. Alumina-supported platinum and halogen is a particularly preferred catalyst for the present reforming reaction, particularly since such composites effect the isomerization of the straight-chain paraffinic hydrocarbon components of the fraction charged thereto into the desirable branched-chain paraffins of higher octane number, dehydroisomerization of the naphthenic hydrocarbon components to aromatic hydrocarbons of high octane number, and the hydrocracking of the higher molecular weight homologs to hydrocarbons boiling in the gasoline range. Other reforming catalyst composites such as alumina-molybdena, alumina-chromia, alumina-zirconia and other catalysts known for this purpose may likewise be utilized in the present reforming stage, although not necessarily with results equivalent to the use of an alumina-platinum-halogen composite. The catalyst composition preferably includes a component which promotes the hydrocracking of the hydrocarbon components and in the preferred alumina-platinum metal composites containing halogen ions, the halogen component acts as the ingredient of the catalyst composition which promotes the hydrocracking reaction. The halogens preferred for this purpose are fluorine and chlorine, present in the composite in an amount of from about 0.01 to about 3% by weight of the composite. The platinum metal is desirably present in the composite in an amount of from about 0.01 to about 1% by weight of the composite. The hydrocarbon charge stock to the reforming reactor, comprising the 275°-400° F. fraction of the natural gasoline feed stock and hydrogen, if desired, is passed over the reforming catalyst, usually in a fixed bed type of reactor, at a liquid hourly space velocity of from about 0.5 to about 10 volumes of vaporized feed stock per volume of catalyst per hour, utilizing a molar ratio of hydrogen to hydrocarbons of from about 0.5 to 1 to about 15 to 1.

The products of the reforming stage are discharged from reactor 12 through line 14 into a

suitable separation zone 15, such as a fractional distillation column, for the recovery of various fractions for individual further treatment. Separation zone 15 may consist of one or more fractional distillation columns in series to accomplish the desired separation. Separation zone 15 is preferably operated under such conditions as to separate a hydrogen stream which may be removed from zone 15 through line 13 and recycled to the reforming zone to provide an atmosphere of hydrogen therein, although hydrogen for this purpose may also be introduced into reforming reactor 12 from other sources, as desired. A gaseous fraction comprising methane, C₂ and C₃ hydrocarbons is removed from separation zone 15 as a light gas through line 16. A fraction containing C₄ and higher hydrocarbon homologs boiling up to about 200° F. is separated in zone 15 and utilized in limited amounts as a low boiling fraction to produce the finished gasoline product of this invention, the amount thereof depending upon the desired Reid vapor pressure of the finished gasoline. This fraction which contains such high octane hydrocarbons as benzene and various isoparaffins such as isopentane and the branched-chain hexanes is removed from zone 15 through line 17 and is diverted into blending or storage tanks wherein the finished gasoline is prepared. A higher boiling fraction having a boiling range, for example, from about 350° to about 400° F. or slightly higher, up to about 415° F. is also incorporated into the finished gasoline blend, the latter fraction being removed from zone 15 through line 18 into a storage or blending tank, or the higher boiling ends, boiling initially at about 160° F. may be cut into line 19 for utilization in alkylation-polymerization reactor 11.

An intermediate boiling fraction of the product formed in reforming zone 12, preferably boiling from about 200° to about 350° F., although lower and higher boiling range limits such as the aforesaid 160° F. initial boiling point may be selected, is removed from zone 15 through line 40 19 and charged, together with the low boiling fraction of the cracking reaction products, which generally have an end boiling point of about 200° F., into alkylation-polymerization reactor 11. The polymerization phase of the reaction occurring in reactor 11 effects polymerization of the olefins present in these fractions to higher molecular weight hydrocarbons of lower volatility and of relatively higher octane number, while the alkylation reaction effects condensation of the low molecular weight olefins in the cracked fraction, such as propylene and butylene, with the aromatic hydrocarbons boiling up to about 350° F. present in the reformate fraction. The polymerization and alkylation reactions are effected catalytically in reactor 11 substantially simultaneously in the presence of a catalyst generally characterized as an acidic material, and preferably a solid catalyst of this type. An effective solid catalyst, well known for promoting polymerization and alkylation at selected reaction conditions is the silico-phosphate composite known generally in the petroleum refining art as a "solid phosphoric acid," comprising a composite of a suitable porous support containing silica, such as fuller's earth, diatomaceous earth, various clays, etc. with phosphoric acid, preferably pyrophosphoric acid, generally containing about 62% of P₂O₅ equivalent of phosphoric acid. The phosphoric acid may also be placed on the surface of silica particles, for example, by periodi-

cally wetting the surface of quartz chips or sand with a liquid phosphoric acid. Solid polymerization catalysts, including certain metallic phosphate salts such as copper pyrophosphate, cadmium orthophosphate, mercury pyrophosphate and others, either individually or supported on a suitable solid support such as alumina, clay, etc. are particularly effective catalysts for fixed bed, continuous flow catalytic reactions, and although primarily polymerization catalysts, also effect alkylation at the selective reaction conditions maintained in reactor 11. The polymerization-alkylation reaction is effected in reactor 11 containing a solid catalyst of the above type at superatmospheric pressures, up to about 2000 pounds per square inch, and preferably at a pressure of from about 300 to about 1000 pounds per square inch, at a temperature of from about 300° to about 750° F. and at an hourly space velocity up to about 10 to 15 volumes of gaseous charging stock per volume of catalyst per hour.

The products of the polymerization-alkylation conversion in reactor 11 are removed therefrom through line 28 and discharged into a suitable separation zone 24, such as a distillation column, for the recovery of certain desired fractions from the product. Unconverted gases, such as propane, etc., are removed from zone 24 through line 22 and may be utilized as a gaseous fuel, or recycled to charging line 10 as a diluent of the olefinic feed stock to reactor 11. A gasoline boiling range fraction having an end boiling point of from about 400° to about 415° F. and including C₄ hydrocarbon components is separated and removed from zone 24 through line 23 which connects with line 13, the latter conduit conveying the gasoline fraction to storage or a blending tank for production of the finished gasoline product. The fraction boiling above the end point of the gasoline product comprising the residue in separation zone 24 is removed from the latter zone through line 24 and charged into cracking reactor 5 wherein the high boiling hydrocarbons contained in the latter fraction are split into lower molecular weight products which enter the stream of hydrocarbons processed in the present flow.

The gasoline boiling range fractions from the various separation zones of the present process which segregate these fractions from the products of the cracking reaction, the products of the reforming reaction and the products of the polymerization-alkylation reaction and which all enter line 12 in the above flow when combined and blended in the proportions produced in each of the above reaction stages produce a highly desirable gasoline blend containing a variable ratio of volatile and higher boiling fractions, the finished gasoline product having a vapor pressure suitable for use as a gasoline motor fuel. The particular combination or reaction stages also produces a product of considerably higher octane number than the natural gasoline feed stock utilized in the process flow.

The present invention is further illustrated with respect to specific embodiments thereof in the following example, which, however, is not intended to define the limits of the variables inherent in the present process nor to restrict the scope of the invention in accordance therewith.

A straight-run gasoline fraction having an end boiling point of approximately 400° F., a 50% boiling point of about 210° F. and containing about 12 volume percent of C₄ hydrocarbons is fractionated to separate a fraction boiling up to about 275° F. from a bottoms fraction comprising the

residue of the gasoline feed stock. The lower boiling fraction (B. P.:C₄-275° F.), representing about 55% of the feed stock, is charged into a thermal cracking reactor at a temperature of 1050° F. and at a pressure of 900 pounds per square inch. The products of the reaction are cooled and fractionated to separate a gaseous fraction containing hydrogen, methane, and C₂ hydrocarbons which is vented to a gas storage chamber. A fraction containing C₃ and higher homologs boiling up to about 200° F. is separately collected and reserved for a subsequent polymerization-alkylation conversion, hereinafter described. A third fraction boiling from 200-400° F. and representing approximately 35% by weight of the initial low boiling fraction separated from the natural gasoline feed stock is separated and reserved for subsequent gasoline blending operations. This fraction individually has a leaded (containing 3 cc. of tetraethyl lead per gallon) research octane number of 93 compared to a leaded research octane number of 85 for the C₄-275° F. natural gasoline fraction utilized as feed stock to the cracking reactor.

The higher boiling fraction of the initial gasoline feed stock, representing approximately 45% by weight of the latter, is charged at a temperature of 940° F., at a pressure of 600 pounds per square inch gauge, together with hydrogen in a molar ratio of hydrogen to hydrocarbons of 4 to 6 and at a liquid hourly space velocity of approximately 2 volumes of feed per volume of catalyst per hour into a tubular reactor containing a pilled catalyst consisting of platinum supported on alumina and containing combined fluoride and chloride. The products of the reaction are passed into a distillation zone to separate a gaseous fraction containing hydrogen, methane and light hydrocarbons up to C₄, a fraction comprising C₄ and heavier hydrocarbons boiling up to about 160° F. which is reserved for subsequent blending in the finished gasoline product hereinafter described, a fraction boiling from 170° to about 350° F. (containing about 35% by volume of aromatic hydrocarbons) which is reserved for subsequent treatment in an alkylation-polymerization reactor and a fraction boiling from 350° to about 400° F. which is reserved for subsequent blending into the gasoline product. The C₃-200° F. fraction of the cracking reaction product (containing a large proportion of olefinic hydrocarbons) and the 170-350° F. fraction of the reforming reaction product are charged into a catalyst-packed tube containing "solid phosphoric acid catalyst" at a temperature of 430° F., at a pressure of 450 pounds per square inch and at a liquid hourly space velocity of 2.5 for the combined polymerization-alkylation reaction. The effluent products of the alkylation-polymerization reactor are separated by distillation into a gasoline boiling range fraction boiling up to about 400° F. which is utilized for preparing the final gasoline blend. A fraction comprising unconverted C₃ hydrocarbons, such as propane, is removed to storage. The distillation residue comprising components boiling above about 400° F. and representing about 10% by volume of the product is recycled to the cracking reactor.

The blend of gasoline boiling range fractions recovered from the cracking, reforming and alkylation-polymerization stages above has a Reid vapor pressure of 5 pounds per square inch, a clear octane number of 90, and a Research Motor Method octane number (containing 3 cc. of tetraethyl lead per gallon added thereto) of 95, com-

pared to the Research Motor Method octane number of the natural gasoline feed stock (containing 3 cc. of T. E. L. per gallon) of 85.

I claim as my invention:

1. A process for improving the volatility and anti-knock properties of an essentially paraffinic gasoline boiling range fraction for use in an internal combustion engine which comprises separating said gasoline into a relatively volatile fraction and a relatively higher boiling fraction, subjecting said volatile fraction to thermal cracking reaction conditions, separating from the product of said cracking reaction a light hydrocarbon fraction having an end boiling point of at least 100° F. and containing normally gaseous and normally liquid olefins, subjecting said higher boiling fraction to a hydrocarbon reforming reaction in the presence of a reforming catalyst, separating an intermediate boiling range fraction from the product of said reforming reaction, combining said light hydrocarbon fraction containing aromatic hydrocarbon and said intermediate fraction and subjecting the resulting mixture to a combination polymerization-alkylation reaction, and blending the remaining normally liquid fractions boiling up to about 400° F. from the products of said cracking, reforming and polymerization reactions to form an improved gasoline motor fuel blend.

2. The process of claim 1 further characterized in that said volatile fraction has an end boiling point of from about 200° to about 300° F.

3. The process of claim 1 further characterized in that said high boiling fraction has an initial boiling point of from about 200° to about 300° F. and an end boiling point corresponding to the end boiling point of said gasoline boiling range fraction.

4. The process of claim 1 further characterized in that said light hydrocarbon fraction is a hydrocarbon mixture comprising propylene, and having an end boiling point of about 200° F.

5. The process of claim 1 further characterized in that said intermediate boiling range fraction separated from the product of said reforming reaction has a boiling range of from about 160° to about 350° F.

6. The process of claim 1 further characterized in that a fraction boiling above about 400° F. is separated from the product of said polymerization-alkylation reaction and recycled to said cracking reaction.

7. The process of claim 1 further characterized in that said light hydrocarbon fraction includes C₃ hydrocarbons and has an end boiling point of about 200° F.
